UNITED STATES PATENT OFFICE

104,581

DESIGN FOR A TUBING FOR LAMP STANDS OR THE LIKE

Nicholas Rainone, Chicago, Ill.

Application March 6, 1937, Serial No. 68,050

Term of patent 7 years

To all whom it may concern:

Be it known that I, Nicholas Rainone, a citizen of the United States, residing at Chicago, in the county of Cook and State of Illinois, have invented a new, original, and ornamental Design for Tubing for Lamp Stands or the Like, of which the following is a specification, reference being had to the accompanying drawing forming a part thereof.

The characteristic features of my design reside in a tubing having relatively large longitudinal intersecting reeds and comparatively narrow lon-

gitudinal surface ornamentation on that part of a reed most remote from the axis of the tubing.

Fig. 1 is an end view of a length of tubing showing my new design.

Fig. 2 is a side elevation of a fragmentary length of the tubing illustrated in Fig. 1.

I claim:

The ornamental design for a tubing for lamp stands or the like, substantially as shown and described.

NICHOLAS RAINONE.
